[57] CLAIM

The ornamental design for an interactive terminal display, substantially as shown and described.

DESCRIPTION

FIG. 1 is a front, top and left side perspective view of a combined interactive terminal display and support therefor showing our new design;

FIG. 2 is a rear, top and right side perspective view thereof;

FIG. 3 is a front, top and left side thereof with the support in an alternate position for mounting on the underside of a shelf;

FIG. 4 is a rear, top and right side perspective view thereof;

FIG. 5 is a side elevational view thereof;

FIG. 6 is a front elevational view thereof.
